(57) **CLAIM**

The ornamental design for a cellphone case with rotating comfort grip, as shown and described.

DESCRIPTION

1. Cellphone case with rotating comfort grip
1.1 is a perspective view of a cellphone case with rotating comfort grip showing our new design;
1.2 is a rear elevation view thereof;
1.3 is a rear elevation view thereof, where the comfort grip is pulled out;
1.4 is a left side elevation view thereof;
1.5 is a left side elevation view thereof, where the comfort grip is pulled out;
1.6 is a right side elevation view thereof;
1.7 is a right side elevation view thereof, where the comfort grip is pulled out;
1.8 is a bottom plan view thereof;
1.9 is a bottom plan view thereof, where the comfort grip is pulled out;
1.10 is a top plan view thereof;
1.11 is a top plan view thereof, where the comfort grip is pulled out;
1.12 is a bottom, rear, and left-side perspective view thereof, where the comfort grip is pulled out;
1.13 is a bottom, rear, and left-side perspective view thereof, where the comfort grip is rotated 180-degrees and pulled out;
1.14 is an exploded bottom, rear, and left-side perspective view thereof;
1.15 is a front elevation view thereof;
1.16 is a perspective view thereof while in use.

(Continued)

The broken line showing of a hand in reproduction 1.16 is provided for the purpose of illustrating environmental structure and forms no part of the claimed design.
